UNITED STATES PATENT OFFICE.

JOSEPH V. WECKBAUGH, OF NEW YORK, N. Y.

ACCOUNTING AND RECORDING APPARATUS.

1,337,575.

Specification of Letters Patent. Patented Apr. 20, 1920.

Application filed February 3, 1913, Serial No. 745,775. Renewed July 18, 1919. Serial No. 311,902.

To all whom it may concern:

Be it known that I, JOSEPH V. WECKBAUGH, a citizen of the United States, residing at New York, in the county of New York and State of New York, have invented new and useful Improvements in Accounting and Recording Apparatus, of which the following is a specification.

My invention relates to apparatus for keeping and recording accounts, and for addressing, dating, and filing of customers' slips and invoices and the like. It may be used merely for addressing, if desired.

The object of my invention is to provide an apparatus of this kind which is easily and reliably operated with but few movements on the part of the operator and with a minimum of chances for inaccuracies. One of the objects is to combine an adding machine with a filing cabinet so as to prevent errors which occur in the usual methods of handling such transactions. Another object is to print the name, or address or both, of the person making credit purchases on a credit slip and at the same time print the total of his purchases thereon. Other objects will appear hereinafter.

On the accompanying drawings, Figure 1 is a plan of an apparatus embodying my invention, the top of the casing being removed; Fig. 2, a side elevation with parts broken away; Fig. 3, a section of Fig. 2 on line III—III; Fig. 4, a plan of the top of the casing with some parts shown in dotted lines; Fig. 5, a detail elevation, parts being broken away, of a part of the elevator; Fig. 6, a perspective view of one of the drawers for credit slips; Fig. 7, a fragmentary view showing the locking and releasing mechanism for one of the drawers; Fig. 8, a section of a portion of the top of the casing, the section beneath the top being taken on the line VIII—VIII, Fig. 9, a plan view of the drawer release mechanism and related parts; Fig. 10, a fragmentary view showing a section of a part of the top of the casing, showing the controller handle and its relation to adjacent parts; Fig. 11, a front view of a portion of a drawer casing with drawers therein; Fig. 12, a fragmentary view showing a portion of one of the galley plates or name and address carrying plates, with its guides and name holding de-

vices; Fig. 13, a horizontal section across a pair of guides and a plan of a galley plate between the guides; Fig. 14, a perspective view of a typeholder adapted to be attached to a galley plate; Fig. 15, a cross-section of a typeholder and type therein; Fig. 16, a view showing the arrangement of the various recording devices; Fig. 17, a plan view of a portion of the adding machine and recording devices; Fig. 18, a plan showing the adding-machine feed rollers provided with means for moving them apart; Fig. 19, an end view of Fig. 18; and Fig. 20, a plan of a portion of my invention, showing a modification.

On the drawings, 1 represents a cabinet supported on legs and having the bottom 2, the top 3, and suitable sides and ends.

On the bottom 2 are the rails 4 on which the wheels 5 of the carriage 6 run. The frame or body of the carriage consists of a casting having the ends 7 and 8, the front 75 9, the rear 10, and the bottom 11. The bottom 11 has the rearwardly projecting fingers 12, on which vertical drawer cases, 13, 14, 15, 16, 17 rest, each case being supported on adjacent fingers and standing over the 80 space between such fingers. Within each case is a vertical series of drawers 18 supported on suitable shelves or partitions 19. These drawers are designed to contain credit slips showing the articles purchased, the 85 prices of each, the name and address of the purchaser and the total amount due.

Near the left hand end of the carriage and just back of the rear end of the cases I locate the four vertical posts 20 arranged at 90 the corners of a rectangle and having their tops and bottoms secured in the top 3 and bottom 2 of the casing. These parts serve as corner guides for the elevator 21 having rollers 22 at its corners bearing against the 95 posts. The elevator has a forward extension 23 located so as to travel up through the space between any two sets of fingers 12 which happens to be over the same. The elevator is secured to the vertical rack-bar 24 100 by means of a set screw (Fig. 5). The upper end of the rack-bar travels up and down through the opening 25 in the top 3. The lower end of the rack-bar has thereon the cross-head 26 having the rear angle 105 arm 27 which carries the vertical pusher 28

for the galleys of names presently to be described.

On the rear side of the carriage 6 are five pairs of vertical guides 29 and between each 5 pair of guides there is a galley plate or name and address carrying plate 30 having vertical grooves in its edges fitting the said vertical guides so that the plates may be guided up and down and securely held in 10 place. Each of the bars 30 is provided with as many horizontal sticks or type-holders 31 as there are drawers in the corresponding series. These sticks contain type 31' (Fig. 15) spelling the names and addresses of the 15 customers to whom the several drawers have been assigned. The names in the several sticks 31 occupy positions on the same corresponding to the positions of the drawers assigned to the customers. The lower ends 20 of the plates 30 may be brought by the movement of the carriage 6 so that any one of them may stand in line with the pusher 28, which, on the raising of the rack bar 24, pushes up whichever plate 30 happens to be 25 over it, this bar corresponding to the series of drawers which have, by the same movement of the carriage 6, been brought over the extension 23 of the elevator 21.

Each plate 30 is provided on its rear face 30 with a series of vertically arranged hooks 30^a, and a series of spring hooks 30^c arranged opposite the hooks 30^a. The hooks 30^c are secured to the front of the plate 30 and extend through holes 30^b. The side of 35 the hooks 30^c facing the hooks 30^a are beveled. The type-holders 31 are inserted between opposite hooks 30^a and 30^c by inserting one end of the holder 31 beneath the hook 30^a and then pressing the other end 40 of the holder down on the bevel of the hook 30^c, which will be forced away and then spring into the end of the holder when the holder is pressed flat against the plate 30. The hooks are made wide enough to fill the 45 ends of the holder 31 so that the latter cannot move up or down on the hooks.

The holder 31 is composed of sheet-metal folded in the middle to form a T-shaped member 31^a. The lateral members are bent 50 away from each other to form the back portions 31^b of the holder. There the lateral members are bent up in the same direction to form the sides 31^c, and then bent toward the member 31^a, thereby leaving the parallel spaces 31^d to receive the necks of the type 55 31', the type being retained in place by the enlarged portions in the space between the sides and the member 30^a. The ends of the member 31^a are removed to accommodate 60 the hooks 30^a and 30^c, which prevent end-wise movement of the type.

The extension 23 is directly under the casing 32 on the top 3, into which the case of drawers resting on the extension 23 move

when the elevator rises. The casing 32 is 65 placed on the top 3 to contain such portion of any case of drawers as rises above the said top, the front of the casing having a front opening 34 just above the top 3 through which any drawer 18 opposite thereto may move, as shown on Fig. 3. The front of each drawer has a swinging front 35 pivoted to the sides thereof, so that it will, when the drawer has moved forwardly, drop down slightly as shown on Figs. 3 and 75 6 to permit a more ready view of and access to the contents of the drawer. When the drawers are in normal positions the fronts 35 are supported by the next lower front or by the partitions 19. A projection 36 bent 80 upwardly from the front end of the bottom of each drawer serves as a stop for the slips therein.

The rear end of each drawer has a horizontal swinging dog or latch 37 having a tooth 38 on its left side adapted to catch over the rear wall of the case as shown on Figs. 1 and 7, the casing 32 having a vertical slot 39, through which the ends of the latches on the drawers move. A coil expansion spring 40 surrounds the dog and is secured to the drawer so as to make it bear against the right-hand side of the catch and push it to the left. The tooth 38 will thereby be moved into locking engagement with the case 17 when the drawer is pushed entirely in (Fig. 7). The spring 40 is compressed between the drawer and the case and serves to push the drawer forwardly as shown in Fig. 3, as soon as the tooth of the 100 catch is pushed out of engagement with the associated drawer case.

A casing 41 is provided above the top 3 to contain the galley or name plates 30, when they are lifted above the top 3.

The teeth on the rack bar 24 mesh with the pinion 42 mounted to turn in hangers 42' on the bottom of the top 3. The pinion 43, mounted on the same shaft with the pinion 42, meshes with the pinion 44 secured 110 to the square shaft 45 mounted in fixed bearings 46 and 47.

The shaft 45 also supports the pinion 48 which moves with the carriage and slides on the square shaft 45. The pinion 48 115 meshes with the spur gear 49 carried by the stub-shaft 50 on the carriage 6. The shaft 50 also supports the sprocket wheel 51, over which and the rear idle sprocket wheel 52 the horizontal sprocket chain 53 runs.

The end 7 of the carriage is provided at the top with a pair of horizontal bars 54 just above the sprocket chain and parallel thereto, these bars serving as a guideway for the block 55, which is attached to the 125 chain 53. On the block 55 is the vertical stud 56 which extends up through the top 3 and travels in the slot 57 therein to move

the carriage back and forth. The handle 58 is pivoted to the top of the stud 56 so as to have movement to the left.

The top 3 is provided with as many branch slots 59 extending forwardly from the slot 57 as there are series of drawers. The names which are on the galley plates 30 and corresponding to the drawers are arranged at the sides of the corresponding slots 59 in the same order and corresponding positions that they occupy in the galley plates. The parts are so proportioned that, when the handle 58 is moved along the slot 57 to any slot 59 and then moved along the latter slot opposite any particular name, the elevator will lift the corresponding case of drawers until the drawer corresponding to the name stands opposite the opening 34 in the case 32, and the corresponding galley plate 30 is raised until the name thereon corresponding to said drawer stands in printing position before the platen 60 of the printing devices.

Suspended on the links 61, which are pivoted to the lower side of the top 3, is the horizontal tripper frame 62 having the fingers or bars 63 lying below and to the right of the branch slots 59, there being as many fingers or bars as there are branch slots. The rear ends of the bars or fingers terminate just forwardly of the main slot 57 so as to be out of the way of the stud 56 and the finger 64 which extends downwardly from the handle 58 and to the right of the stud 56 and stands close to the left side of one of the bars 63 when the handle 58 is in one of the slots 59. The frame 62 has the extension 65 which terminates just to the left of the position in which any dog 37 stands when the drawer which it locks in its casing is opposite the slot 34.

66 is an adding machine of any desired make having the usual keys 67, and the usual operating handle 68, the usual total wheels 69, and the feed rollers 70 and 71 for the double record strips 72 and 73, wound from the reel or roll 75 onto the reel or roll 74. 76 is the ordinary carbon printing ribbon on the adding machine and 77 is an additional carbon ribbon parallel with and back of the ribbon 76. 78 is the carbon half or copy of the customer's invoice slip, which shows the articles purchased and their prices, written out by the storekeeper or clerk when the purchases are made, the writing being made on an "original" slip provided with a carbon back which makes a copy on the customer's carbon slip in a manner well known. The "original" slip 79 (Fig. 1) is kept in the customer's proper drawer 18 except as hereinafter stated.

A pair of cams 80 are attached to the yoke 81 so that, when the yoke is rocked by the handle 82, the cams will spread the rollers

70 and 71 in order that the customer's slip 65 78 may be dropped between the rollers and also between the ribbons 76 and 77. The slip drops down till it rests on the stop 83.

84 represents the printing bar for the prices of the items purchased and 85 the platen for causing the prices on the bar 84 to be printed on the strips 72 and 73, and the customer's slip. The actuating means for the various printing wheels, ribbons, strips, and platens are well known and the presence of these various elements are indicated conventionally merely to denote their presence without attempting to show completely their actual construction or their connection with other parts.

When a customer makes credit purchases, the salesman writes the items and the prices on a sales slip beneath which is a duplicate slip. The back of the sales slip, hereinafter called the original slip, is carbonized or a carbon paper is inserted between the two slips, so that the customer's slip will contain a copy of the items and prices which have been placed on the original slip. The clerk detaches the original slip and puts the duplicate or customer's slip between the feed rolls 70 and 71, between the inking ribbons 76 and 77, and upon the rest 83, which he is able to do by moving the handle 82 and thereby separating the rollers. The handle 58 is moved along the slot 57 until it comes in line with that slot 59, along which the customer's name is found. This movement of the handle moves the carriage 6 along the rails 4 until the case of drawers containing the customer's drawer comes beneath the casing 32, and until the galley plate 30 bearing the customer's name comes beneath the casing 41.

The handle 58 is moved along the said slot 59 until the pointer 86 is opposite the customer's name on the index. By this movement of the handle, the said drawer case is moved up through the top 3 and into the casing 32 until the customer's drawer 18 stands opposite the opening 34, and the said galley plate 30 is moved up through the top 3 and into the casing 41 until the customer's name stands opposite the platen 60 which is the usual total wheel platen extended so as to lie opposite any elevated galley plate. The handle 58 is moved to the left which causes the finger 64 to move the tripping frame 62 to the right, whereupon the end of the extension 65 pushes the dog 37 on the customer's drawer to the right until the tooth 38 is moved out of engagement with the drawer casing. The spring 40 surrounding this dog is then free to expand. It forces the customer's drawer forwardly where the salesman can have access to it, the front 35 dropping slightly as explained. The salesman operates the adding machine

to print the amount of the items at the right hand side of the customer's slip and in line with the amounts originally placed thereon by the salesman. He also places on the slip 5 the total of former purchases, if any, not paid for, as disclosed by the top slip in the said drawer, and then causes the total to be printed on the slip. The name and address or other data on the galley plate are also 10 printed on the slip at the same time the total is printed, the operation of the name and address printing mechanism being controlled by the total key of the adding machine. At the same time the adding machine 15 is printing on the slip, it is also printing the amounts of the items and the total of the same and previous unpaid totals, together with the name and address of the customer, on the strips 72 and 73, the back of 20 the strip 72, being carbonized. As the printing proceeds from line to line on the slip, the slip and the strips 72 and 73 are fed upwardly by the rollers 70 and 71 as is the case with record strips in adding machines 25 now in use. The rear ribbon 77 prints the data on the strip 72 and the front ribbon 76 prints the data on the customer's slip.

The customer's slip is taken from the machine and handed to him and the end of the strip 72 is torn off and filed away in the purchaser's drawer with the original slip. The strip 73 remains on the roll 74.

The drawer is pushed back into its case where it is locked by its dog 37, the tripping frame having been moved to the left by gravity. The apparatus is now ready for another cycle of operation.

The casing 1 is preferably composed of fire-proof material to protect the records within the same.

On Fig. 20. I have shown the drum 87 provided with annular areas 88, 89, 90, 91, 92, on which the names and addresses are arranged in the same order as on the galley strips 30. The matter and the arrangement thereof on the first area 88 is the same as on the first or left hand galley strip 30 and the matter on the second area 89 is the same as to subject matter and arrangement as 45 on the second galley strip 30, and so on with the rest of the areas 90, 91 and 92.

On the square shaft 45 I place the sprocket wheel 93 slidable on the said shaft, the same as the pinion 48. A sprocket chain 94 runs from the sprocket wheel 93 over the sprocket wheel 95 on the shaft 96 of the drum. It is thus seen that the drum will slide right and left with the carriage since the parts are carried by the end 7 thereof. 55 As the shaft 45 is rotated by the operation of the controlling handle 58 the drum 87 will be rotated so as to bring the proper name and address before the printing platen. It is clear that the drawers or the adding

machine or both may be omitted and that 65 the drum 87 or the plates 30 may be used for the printing of names or names and addresses corresponding with those selected by the handle 58.

While I have described my invention minutely in its details and the combinations thereof, I do not desire to be restricted to the same except as the claims specifically require the same.

I claim—

1. A casing having a slot therein, a receptacle carrier supporting a series of superposed receptacles, an index of the receptacles arranged along the slot, means having travel longitudinally of the slot and causing, by its movement to any index indication, a movement of the receptacle carrier to bring the corresponding receptacle to a definite position above the casing, and means associated with the aforesaid means for releasing the particular receptacle whereby it is permitted to move from its position in the tier of superposed receptacles to a second position to receive a check.

2. An index, a device registrable with any indication thereon, a drawer casing, a series of drawers therein, means for locking each drawer in the casing, and means operable by the said device at any position thereof for tripping the locking mechanism of any drawer.

3. An index, a device registrable with any indication thereon, a drawer casing, a series of drawers therein, means for locking each drawer in the casing, means operable by the said device at any position thereof for tripping the locking mechanism of any drawer, tripping means being returned by gravity to normal position and out of the path of the locking means.

4. An index, a device registrable with any indication thereon, a drawer casing, a series of drawers therein, means for locking each drawer in the casing, a casing into which the drawer casing may enter, means controlled by the said device for moving the drawer casing into the other casing and any drawer corresponding to the selected indication in line with a discharge opening in the latter casing, and means for releasing the locking means of any drawer in line with the said opening.

5. A carriage, a series of casings supported thereon and arranged in a line parallel with the travel of the carriage, an elevator 120 normally below the drawer casings and having travel longitudinally of the casings, a series of movable devices in each casing, an index of the movable devices, having indications arranged to correspond to the arrangement of the casings and the said devices, an actuator movable to any position corresponding to any indication on the in-

- dex, and connections for causing the movements of the actuator to move the carriage so that the casing containing the selected movable device shall be above the elevator, 5 and for causing the elevator to move the casing a distance corresponding to the position of the said device in the casing.
6. A series of movable elements, a locking means for each element, a casing having a slot therein, an index of the movable elements arranged along the slot, a device movable in the slot to bring to a fixed position any element indicated by the device, and means actuated by the said device for 10 releasing the locking means for the indicated element.
7. A series of movable elements, a locking means for each element, a casing having a main slot and a plurality of branch 15 slots, an index of the movable elements arranged along the branch slots, a device movable in the main and branch slots, and means actuated by the said device when at any one of the indications on the index for releasing 20 the locking means for the indicated element.
8. A series of movable elements, a locking means for each element, a casing having a main slot and a plurality of branch 25 slots, a device movable in the main and branch slots, an index of the movable elements arranged along the branch slots, and means actuated by the said device when at any one of the indications on the index, for 30 releasing the locking means for the indicated element.
9. A casing top having a main slot and a plurality of slots branching therefrom, a frame supported by links, the frame having 35 a member parallel to each branch slot, a series of movable elements, an index of the movable elements arranged along the branch slots, a locking means for each element, arranged to be released by the said frame 40 when swung on its links, a pivoted handle movable along the said slots, and a finger on the handle arranged to engage the adjacent frame member and move the frame when the handle is swung on its pivot.
10. In a device of the character described, 45 a movable carriage, receptacle carriers supported thereon, means for moving a selected receptacle carrier independently of movement of the carriage to bring a selected receptacle in said carrier to operative position.
11. In a device of the character described, 50 a movable carriage, receptacle carriers supported thereon, and a device adapted to move the carriage and also to move a selected receptacle carrier independently of movement of the carriage.
12. In a device of the character described, 55 a movable carriage, receptacle carriers sup-
- ported thereon, means for locking the receptacles in the carriers, means for moving a selected receptacle carrier independently of movement of the carriage to bring a selected receptacle to operative position, and means for releasing the locking means for 60 said receptacles.
13. In a machine of the class described, in combination; a plurality of groups of check receptacles; and a means for selecting any one group of check receptacles, said means 65 being movable to thereafter select one receptacle from the previously selected group.
14. In a machine of the class described; in combination; a plurality of groups of check receptacles; movable means for selecting one receptacle from a previously selected group; and means for thereafter positioning the said receptacle to receive a check.
15. In a machine of the class described, in combination; a plurality of groups of check receptacles; variably movable means for moving the receptacles in one direction, to select an individual receptacle from a previously selected group; and means for thereafter moving the said receptacle in a different direction to receive a check.
16. In a machine of the class described in combination, a plurality of groups of independent check receptacles; an adjustable means for first selecting one of the groups of receptacles and thereafter selecting one receptacle from the group; and means associated therewith for thereafter positioning the receptacle in a position to receive a check.
17. In a machine of the class described, in combination a plurality of groups of check receptacles; a carrier to elevate any one group of the said receptacles; a variably set member to predetermine the group of receptacles elevated by the carrier; said member having a second variable setting to predetermine the extent of elevation of a group of receptacles whereby a certain receptacle is moved to operating position.
18. In a machine of the class described, in combination a plurality of groups of check receptacles; a carrier to elevate any one group of the said receptacles; a variably set member to predetermine the group of receptacles elevated by the carrier; said member having a second variable setting to predetermine the extent of elevation of a group of receptacles whereby a certain receptacle is moved to operating position; and means associated with the variably set member for releasing the receptacle in operating position, whereby the said receptacle can move to a position to receive a check.
19. In a machine of the class described in combination; a table having a series of slots therein; and indices adjacent thereto; a variably positionable manipulative member

movable in the said slots adjacent the indices; a group of check receptacles; and operating devices associated with the said member for moving the group of receptacles to thereby select one receptacle therefrom corresponding to the particular graduation of the index adjacent the variably set member; means associated with the variably set member to release the said selected recep-

tacle; and means to thereafter move the 10 said selected receptacle to a position to receive a check.

Signed at Pittsburgh, Pa., this 20th day of January, A. D. 1913.

JOSEPH V. WECKBAUGH.

Witnesses:

ALICE E. DUFF,
ELVA STANICK.

It is hereby certified that in Letters Patent No. 1,337,575, granted April 20, 1920, upon the application of Joseph V. Weckbaugh, of New York, N. Y., for an improvement in "Accounting and Recording Apparatus," an error appears in the printed specification requiring correction as follows: Page 4, line 103, claim 3, before the word "tripping" insert the word *said*; and that the said Letters Patent should be read with this correction therein that the same may conform to the record of the case in the Patent Office.

Signed and sealed this 25th day of May, A. D., 1920.

[SEAL.]

M. H. COULSTON,

Acting Commissioner of Patents.
